DESIGN FOR AN EYESHADE OR SIMILAR ARTICLE

Carlos J. Cardona, Los Angeles, Calif.

Application October 6, 1943, Serial No. 111,282

Term of patent 14 years

To all whom it may concern:

Be it known that I, Carlos J. Cardona, a citizen of the United States, residing at Los Angeles, in the county of Los Angeles, State of California, have invented a new, original, and ornamental Design for an Eye-shade or Similar Article, of which the following is a specification, reference being had to the accompanying drawing, forming part thereof.

My design for an eye-shade is characterized by the configuration of the front of the same, being of a unitary piece of material and having rearwardly extending sides, top and bottom edge portions.

Fig. 1 is a front perspective view of an eye-shade showing my new design;

Fig. 2 is a rear perspective view of the eye-shade.

Fig. 3 is a transverse section taken along the plane III—III in Fig. 1.

I claim:

The ornamental design for an eye-shade or similar article, substantially as shown and described.

CARLOS J. CARDONA.
